No. 646,585.

Patented Apr. 3, 1900.

J. E. QUATSOE & W. BEIER.

PORTABLE DARK ROOM.

(Application filed Mar. 27, 1899.)

(No Model.)

UNITED STATES PATENT OFFICE.

JOHN E. QUATSOE AND WALTER BEIER, OF JANEVILLE, WISCONSIN.

PORTABLE DARK ROOM.

SPECIFICATION forming part of Letters Patent No. 646,585, dated April 3, 1900.

Application filed March 27, 1899. Serial No. 710,591. (No model.)

To all whom it may concern:

Be it known that we, JOHN E. QUATSOE and WALTER BEIER, citizens of the United States, residing at Janesville, in the county of Rock 5 and State of Wisconsin, have invented new and useful Improvements in Portable Dark Rooms, of which the following is a specification.

Our invention relates to improvements in 10 portable dark rooms for developing photograph plates and films.

The object of our invention is to provide an inclosure of such small dimensions that it 15 may be readily carried from place to place with a portable camera, whereby the amateur or professional photographer is enabled to develop and finish pictures taken by him outdoors or wherever he may chance to be, thus avoiding the necessity of using the ordinary dark room of the photographer.

The construction of our device is further explained by reference to the accompanying drawings, in which—

Figure 1 represents a longitudinal vertical 25 section. Fig. 2 is a vertical cross-section of the dark room as it appears when drawn out or extended in position for use. Fig. 3 is a perspective view of the plate-holder removed from the dark room. Fig. 4 is a detail showing the device for locking the cases in their 30 opened and closed positions.

Like parts are referred to by the same reference-letters throughout the several views.

A is the exterior case, which when the device 35 is not in use is closed down over the lower or inner case B, when the two cases are locked together by the catch or button C, which is secured to the lower edge of the upper case A and is adapted to engage beneath 40 the bottom of the case B when the cases are in the closed position. When the two cases are thus locked together, they may be readily carried from place to place by the handle D.

When desirous to use the dark room, 45 the catch or button C is disengaged from beneath the bottom of the case B. The exterior case is then drawn up, as shown in Figs. 1 and 2, when it is locked in said position by turning said button or catch C into the retaining notch or recess E provided therefor at the upper edge of the lower case B.

To enable the operator to handle the sen-

sitive plates and other apparatus within the cases without admitting light thereto, we have provided the lower case B with sleeves F F 55 for the reception of the arms of the operator. The sleeves F are respectively secured at their inner ends to the lower case B around the hand-holes G G by tacks or other equivalent means, as indicated. To avoid withdrawing the hands when developing the plates, we have provided the case with the necessary apparatus for holding and treating such plates.

H is a light-tight receptacle in which the 65 sensitive plates are stored preparatory to use. The receptacle H after being filled with plates is closed with the cover I. The upper edge of the receptacle H is provided with outer projecting flanges J J, which engage in the supporting-ways K K. The receptacle H, having been supplied with the sensitive plates and the cover I closed, it is suspended, as indicated in Fig. 2, from the supporting-ways K of the case-cover L. 75

For convenience in treating the plates with- 80 in the dark room we have provided a recep- tacle or so-called "developer-tray" M, which is preferably suspended from the side of the inclosing case B from the rod N by hooks O O, which permit such developer-tray to be moved from one end to the other of the dark room, as may be found convenient. When the plates have been immersed in the liquid of the developer, they are removed therefrom 85 and placed successively in the corrugations or grooves P P of the plate-holder Q, when the plate-holder is then placed in the recep- tacle or so-called "hypotray" R for further development. After the plates have been 90 left the required length of time in the hypotray they are removed with the holder Q, when the same are withdrawn from the dark room. The hypotray is provided with a tight cover. 95

To facilitate the operator in drawing the sleeves over his arms and at the same time to prevent light entering through such sleeves, they are closed at their ends S and provided with side openings T, through which the operator inserts his arms preparatory to han- 100 dling the plates.

The developing-tray M is preferably pro- vided with a scale or series of index-marks

by which the operator is enabled to supply the developing-tray with the required proportions of the ingredients used without measuring the same. The respective ends of 5 the case B are provided with ruby-colored glass plates U or plates of such other color as will exclude the injurious light-rays from the sensitive plates. The developing-tray M is preferably formed of glass or other transparent substances that the operator may watch 10 the development of the plates. The tray M is also provided with a water-tight cover or stopper to prevent the liquid from spilling when carried.

15 To facilitate removing the plates from the developer-tray, the same is provided with a lifting-bracket V, which may be formed from a single piece of wire bent in the shape indicated. The bracket V is provided with a 20 horizontal projection W, which engages beneath the lower edge of the sensitive plate when emersed in the developing-tray. Thus it will be obvious that by throwing the bracket V from the position shown in Fig. 1 to the 25 vertical at the right of the developing-tray the sensitive plate, which rests upon the projection W, will be raised from the developing-tray in position to be grasped by the hand of the operator, when it is removed and placed, 30 as previously stated, in the plate-holder Q, when the bracket V is permitted to drop back in the position shown.

In the construction of the cases A and B and the receptacle H care is taken to so form 35 the joints that the light will be excluded.

Having thus described our invention, what we claim as new, and desire to secure by Letters Patent, is—

1. In a portable dark room, the combination 40 of an exterior telescoping case A; plate-receptacle H suspended by supporting-ways from the inner upper wall or top of said receptacle; catch or button C pivoted to the lower edge of said exterior case; interior case B provided with a retaining notch or recess E for the 45 reception of said catch or button; said cases

being adapted to be telescoped together and locked in both their closed and extended positions by said catch, substantially as and for the purpose specified. 50

2. In a portable dark room, the combination 55 of an exterior telescoping case A; plate-receptacle H suspended by supporting-ways from the inner upper wall or top of said receptacle; catch or button C pivoted to the lower edge of said exterior case; interior case B provided with a retaining notch or recess E for the reception of said catch or button; oppositely-arranged sleeves F, respectively secured at their inner ends to said interior case 60 B, around the hand-holes G, G; said cases being adapted to be telescoped together and locked in both their closed and extended positions by said catch, substantially as and for the purpose specified. 65

3. In a portable dark room, the combination 70 of an exterior telescoping case A; plate-receptacle H suspended by supporting-ways from the inner upper wall or top of said receptacle; catch or button C pivoted to the lower edge of said exterior case; interior case B provided with a retaining notch or recess E for the reception of said catch or button; oppositely-arranged sleeves F, respectively secured at the inner ends to said interior case 75 B, around the hand-holes G, G; oppositely-arranged colored-glass plates forming sides to said interior case; and a transparent developing-tray located between said colored-glass plates, all substantially as and for the 80 purpose specified.

In testimony whereof we affix our signatures in the presence of witnesses.

JOHN E. QUATSOE.
WALTER BEIER.
